BAG MOUTH EXPANDER

Filed March 6, 1922

Inventors:

ALFRED J. LAGRANDEUR
EDWARD C. ANDERSON

By their Attorney

James J. Williamson

UNITED STATES PATENT OFFICE.

ALFRED J. LA GRANDEUR AND EDWARD C. ANDERSON, OF SOMERSET, WISCONSIN.

BAG-MOUTH EXPANDER.

Application filed March 6, 1922. Serial No. 541,479.

To all whom it may concern:

Be it known that we, ALFRED J. LA GRANDEUR and EDWARD C. ANDERSON, citizens of the United States, residing at Somerset, in the county of Saint Croix and State of Wisconsin, have invented certain new and useful Improvements in Bag-Mouth Expanders; and we do hereby declare the following to be a full, clear, and exact description of the invention, such as will enable others skilled in the art to which it appertains to make and use the same.

This invention relates to a bag opener or to a device adapted to be placed in the top of a bag or sack and to hold the same open during the filling operation. While the device can be made of a size and material to suit bags of various sizes and material, it is particularly designed to be used with the ordinary paper bags which are used in stores and groceries for carrying various loose materials.

It is an object of this invention to provide an automatically expanding member adapted to engage the bag around its top inner edge, which member is provided with a convenient and efficient manipulating means projecting therefrom.

It is more specifically an object of the invention to provide an automatically expanding band having a pair of pivoted scissor-like handles attached, one at each end of the band, so that the band can be readily contracted and placed in the bag.

It is still another object of the invention to have the said handles disposed in a plane offset from the plane of the band so that the said handles will conveniently project over the top edge of the bag. These and other objects and advantages of the invention will be fully set forth in the following description made in connection with the accompanying drawings in which like reference characters refer to the same parts throughout the different views, and in which

Fig. 1 is a view in elevation of a bag showing the device therein;

Fig. 2 is a view in side elevation of the device;

Fig. 3 is a plan view of the device in contracted position; and

Fig. 4 is a plan view of the device in expanded position.

Referring to the drawings, the device is

seen to comprise a ring or band member 1, 55 which, in the embodiment of the invention, illustrated, is shown as made of a flat strip of resilient material bent into substantially the form of a hoop. The ends of this band are attached to the ends of handle members 60 2 and 3 which are pivoted by a convenient screw or rivet at 4 and provided on their outer ends with scissor-like handles comprising the finger holds 5. It will be noted that the main portions of the handle members 2 65 and 3 have their ends downturned at substantially a right angle so that the said handles are disposed in a plane offset at some distance from the plane of the hoop formed by member 1. The ends of the handles are of 70 somewhat enlarged substantially cylindrical shape and have flattened portions 2^a, and the ends of the band 1 are bent around these flattened portions. The ends of the band are thus held from vertical movement on the 75 ends of the handles and are furthermore, given a bearing thereon of considerable length so that the band is effectively kept from twisting relatively to the handles. The band will thus always be maintained with its 80 flat surface extending substantially normal to the plane of the hoop formed thereby. It will also be noted that the main straight portion of the handle 2 is slightly longer 85 than the similar portion of the handle 3 so that when the hoop is brought to contracted position, as shown in Fig. 3, the ends thereof are engaged to form a stop so that the handles will not move to reversed or crossed 90 position.

In operation, the bag will be held by one hand and the device will be held in the other with the fingers engaged through the finger holds 5. The device will be contracted, as shown in Fig. 3, and may thus readily be inserted into the bag. The handles are then released or allowed to separate as the hoop 1 expands and the latter will engage the sides of the bag and expand the same into substantially wide open position. The outer sides of the band are formed with outwardly projecting punch portions or points 1^a to give a friction surface to engage the sides of the bag, so that the device will be frictionally held therein by its own expansive force. After the device is engaged in the sack or bag, as illustrated in Fig. 1, it will be maintained therein without any further holding by the 100 105

operator and the bag can then be filled, as desired. The device has very little weight and can be easily manipulated to be placed in the bag and will thus readily maintain its position therein. The handle portions project over the top edge of the bag owing to their offset portions and no part of the device is in the way in the filling operation.

From the above description it is seen that 10 applicants have provided a simple and efficient bag opening device and one that can be very inexpensively made. As stated, the same can be made in various sizes and weights to suit the type of bag with which 15 it is to be used. The utility and efficiency of the device have been clearly demonstrated in actual practice.

It will, of course, be understood that various changes may be made in the form, details and arrangement of the device without departing from the scope of applicants' invention, which, generally stated, consists in the matter shown and described and set forth in the appended claims.

25 What is claimed is:

1. A bag mouth opener comprising a resilient band bent to form an expansible hoop, and lever manipulating means adapted to be grasped in one hand secured to the ends

thereof extending laterally therefrom substantially parallel to the plane of the hoop.

2. The structure set forth in claim 1, said manipulating means being offset from the plane of said hoop whereby the means will project over the top edge of the bag when 35 the hoop is disposed therein.

3. A bag mouth opener comprising a resilient band bent to form an expansible hoop, a manipulating member secured to each end of said band, said members being pivoted together and having handles outside of said pivot whereby the said handles formed as a pair of scissors handles may be moved together to contract said hoop and said hoop will automatically expand to separate said 45 handles.

4. The structure set forth in claim 3, the lengths of the handles between the said pivot and the ends of the band being different.

5. The structure set forth in claim 3, the 50 ends of the handles to which the ends of the band are connected being down-turned at substantially a right angle to their main portion.

In testimony whereof we affix our signatures.

ALFRED J. LA GRANDEUR.
EDWARD C. ANDERSON.
